DESIGN FOR A SHOULDER CAP FOR BROOMS

John H. Hofmann, Sinking Spring, Pa.

Application July 25, 1945, Serial No. 120,943

Term of patent 14 years

(Cl. D9—2)

To all whom it may concern:

Be it known that I, John H. Hofmann, a citizen of the United States, residing at Sinking Spring, in the county of Berks and State of Pennsylvania, have invented a new, original, and ornamental Design for a Shoulder Cap for Brooms, of which the following is a specification, reference being had to the accompanying drawing, forming part thereof.

Fig. 1 is a side view of a Shoulder Cap for Brooms showing my new design.

Fig. 2 is an end elevational view thereof; and Fig. 3 is a top plan view thereof.

I claim:

The ornamental design for a shoulder cap for brooms, as shown.

JOHN H. HOFMANN.
